UNITED STATES PATENT OFFICE.

WILLIAM A. EATON, OF MARCELLUS, MICHIGAN.

SECTIONAL DESK.

SPECIFICATION forming part of Letters Patent No. 484,357, dated October 11, 1892.

Application filed March 19, 1892. Serial No. 425,527. (No model.)

To all whom it may concern:

Be it known that I, WILLIAM A. EATON, a citizen of the United States, residing at Marcellus, county of Cass, State of Michigan, have 5 invented a new and useful Sectional Desk, of which the following is a specification.

This invention relates more particularly to that class of heavy office-desks which has a lower part containing drawers, with a central 10 separation for the feet, and an upper section, which in many instances is closed by a sliding or revolving cover, the upper portion of said desk comprising pigeon-holes and the top of the desk proper, upon which the writing is 15 done.

The object of this invention is to facilitate the handling of said desks, so that they can be more easily carried, and make it possible to 20 pass them through doors otherwise too narrow. This I accomplish by the below described and claimed construction of a sectional desk, and in which description other objects will appear.

In the drawings forming a part of this specification, Figure 1 is a rear elevation of the class of desk referred to. Fig. 2 is a plan view of Fig. 1, with the upper portion above the letters *e e* removed. Fig. 3 is a plan view of the lower portion of the desk in Fig. 1, with 25 the portions of the desk above *c c* removed and showing parts detached. Fig. 4 is a perspective view of a broken portion of the front side of the desk enlarged. Fig. 5 shows an enlarged plan view of parts in Fig. 4, with a 30 portion of the desk in section on line 1 1; and Fig. 6 is a detail showing the fastening device *n* and nut *z*, parts of the desk being shown in section.

The lower portion of the desk, in which the 35 drawers are located, consists of two end chests *A A*, separated from each other by a frame *C*, and a back board *B*, detachably connected with the upper ends of said chests. This back board is employed for the purpose of leaving 40 a space between it and the frame *C* for the sliding or revolving cover (said cover not being here shown) employed in the tops of certain closed desks; but as this forms no part 45 of my invention, when the sliding cover referred to is not employed, the back board may in many instances be dispensed with.

Each end of the frame *C* is provided with

dowels *f f*, which detachably fit into holes in the chests when the frame and chests are connected together, as at the left in Fig. 3. The 55 dowels *s* in Fig. 1 will serve to illustrate the idea, showing how they enter the holes in the woodwork of the chests.

The back board *B* is provided at each end with dowels *s*, which detachably fit into holes 60 in the chests in the same manner as do the dowels *f* referred to. In order to hold these parts securely and yet detachably together, I provide each of the chests with screw-threaded 65 projections *i i*, which projections pass through holes in the ends of the frame *C* and are provided with thumb-nuts, as in Fig. 3.

In order to fasten the top board *D* onto the chests *A A*, I provide said chests with a suitable number of upwardly-projecting pins, 70 which pass up through holes in the ends of the top board *D*, which projections *n* are provided with nuts *z*, which screw down onto the top board. These projections *n* may be attached to the chest *A* in any suitable manner 75 after the nuts *z* are placed on. A convenient way is to screw-thread the lower ends of the projections *n* and screw them into the chest *A*, as clearly shown in Fig. 6. The projections *n* are headed at the upper end for 80 the purpose below stated.

The top of the desk, which contains the pigeon-holes, is shown at *E*, commonly styled a "globe" top.

So far as the construction thus far described 85 is concerned, this or any other style of top, or no top at all, may be employed and still produce a desk of detachable parts; but the plan of detachably connecting the top *E* with the top of the desk, as here shown, will in some 90 instances dispense with the use of the nuts *z*, the latter being especially desirable in very heavy desks, requiring to have the parts more firmly held. The projections *n* referred to extend up into holes made in the under side 95 of the top *E*, said holes being illustrated at *t* in Fig. 5. Mortises *h* are formed in the sides of the top *E*, which mortises intercept the holes *t*.

At *W* is shown a key consisting of a rail 100 having forked projections *v*, which detachably fit into the mortises *h* beneath the heads of the projections *n*, thus detachably attaching the top part *E*. A space is left between

the rail and the side of the top E for holding envelopes, paper, and the like. When removing the desk, the keys W are removed and the top E taken off. Next the top board 5 D is removed and then the chests A are separated from the frame C and the back board B, when all the parts can be carried separately up flights of stairs and through narrow passage-ways and doors, after which the parts 10 are all put together again, making as perfect and fine appearing a desk as though all the parts were made solid by glueing or otherwise in the first place.

In Fig. 1 are shown two doors F F, one 15 hinged to one of the chests A and the other to the other, so as to swing around against the inside of the chests when open and when detaching said chests. These doors are at the rear side of the desk and are employed to 20 close the space between the chests or drawer compartments A or to leave it open, as desired.

Having thus described my invention, what I claim as new, and desire to secure by Letters Patent of the United States, is—

A desk comprising separated chests detachably connected together and having upwardly-extending projections at the ends, a top board having a series of holes fitting over the said projections, said projections being headed, a pigeon-hole compartment having the 25 vertical holes, and the side mortises intercepted by said holes, and a key having the forked projections adapted to enter said mortises and catch beneath the heads of said projections, substantially as set forth.

In testimony to the foregoing I have hereunto subscribed my name in the presence of two witnesses.

WILLIAM A. EATON.
